UNITED STATES PATENT OFFICE.

LEOPOLD KACZANDER, OF NEW YORK, AND ROBERT RUDDY, OF MOUNT VERNON, ASSIGNEES TO THE NATHAN MANUFACTURING COMPANY, OF NEW YORK, N. Y.

INJECTOR.

SPECIFICATION forming part of Letters Patent No. 445,642, dated February 3, 1891.

Application filed December 24, 1890. Serial No. 375,700. (Model.)

To all whom it may concern:

Be it known that we, LEOPOLD KACZANDER, of the city, county, and State of New York, and ROBERT RUDDY, of Mount Vernon, in the county of Westchester and State of New York, have invented certain new and useful Improvements in Injectors, of which the following is a specification.

This invention relates to injectors designed for use on locomotive-engines, and more particularly to such as are termed "non-lifting injectors"—that is, in which the water-supply tank is higher than the water-inlet opening to the injector, so that the water will freely flow to the injector by gravitation, without the aid of a vacuum, as in so-called "lifting injectors."

The purpose of this invention is to make this kind of injectors simpler in operation and more effective and reliable under adverse circumstances.

In non-lifting injectors as heretofore constructed the overflow of the injector, through which the surplus water is allowed to escape at the start, has been placed, as has the injector itself, below the lowest level of the supply-tank. This practice makes it necessary to close the water-regulating valve of the injector whenever the injector is stopped in order to prevent the loss of water which otherwise would result from the flowing out of the water from the tank through the overflow. Again, this practice results in great loss of water in starting the injector, since after the water-valve is opened it takes some time to adjust it to its right position relatively to the steam-pressure carried, and during this time the water issues freely through the overflow; and again, even after the water-supply has once been regulated in proportion to the steam-pressure used, this regulation will be destroyed as soon as the injector stops, because whenever the injector is stopped the water-regulating valve must be closed, as just explained. Consequently the water-valve must be newly adjusted at every start of the injector. Furthermore, the overflow being situated out of sight, the engineer or fireman of a locomotive finds it very difficult to ascer-

tain whether the injector has started promptly 50 or not. All these drawbacks to the use of non-lifting injectors are successfully overcome by our present improvements.

Another defect of non-lifting injectors is that when, through some defect in the steam-valve of the injector, steam leaks into the water-supply pipe heating the water the injector is very difficult to start. We have discovered that by employing a priming-jet, similar to the lifting-jets in lifting-injectors, 55 60 this difficulty is successfully overcome.

Our improvements will be more clearly understood by reference to the accompanying drawings, of which Figure 1 is a vertical longitudinal section through the injector. Fig. 65 2 shows on smaller scale as much of a locomotive and tank as is necessary to illustrate the relative positions of the injector, its overflow, and the level of the water in tank.

A is the body of the injector, preferably 70 cast in one piece.

B, C, and D are the usual connections for the steam, water-supply, and delivery to boiler.

In Fig. 1 the steam-pipe is shown as connected with the side of the body of the injector. In Fig. 2 this pipe is shown as coming from the back of the body to avoid confusion.

E is the steam-nozzle; F, the priming-jet; 80 G, H, and I, the usual intermediate, condensing, and delivery nozzles.

At K we employ an ordinary check-valve to prevent the backflow of water from the boiler.

The priming-jet F is cast in one with a valved disk L, which controls the admission of steam into nozzle E, and this disk is again seated for another valve M controlling the admission of steam into nozzle F. Valve M is 90 preferably made in one with screw-spindle N, which is guided in an ordinary bonnet and stuffing-box O. Into the upper end of disk L screws the nut P, which limits the movement of valve M, and by means of which 95 valve L is lifted when the spindle is screwed out to its full limit. On the top of screw-spindle N is what is called a "universal joint"

Q, from which rod R with a handle S extends into the cab of the locomotive to be conveniently operated by the engineer.

The admission of water to the injector is controlled by a valve T and screw-spindle U, which is also provided with a universal joint V and extension-rod V', which again at a suitable point in the cab is provided with a handle W for operating it. In all these particulars the injector does not differ materially from the one for which Letters Patent of the United States No. 387,599 were granted to us on August 7, 1888.

At a point X of the body of the injector where ordinarily the overflow would be attached, we screw a pipe Y, which we extend to a point situated above the highest level of the water in the tank of the locomotive-tender, as seen in Fig. 2, and at this elevated point we attach the overflow Z, which is provided with the usual check-valve a, to prevent the admission of air after the injector has been started, and with a screw-spindle b and arm c, by means of which the valve a may be tightly closed, if necessary. The arm c is so constructed that a rod d extending into the cab can be attached to it. The water from the overflow runs, as usual, through a funnel e and waste-pipe f into the ash-pan of the boiler of the locomotive.

It will be seen that by thus elevating the overflow of a non-lifting injector above the highest level of the water in the tank, the water cannot be lost from the tank when the injector is not working, even if the water-valve T is left open. The continuous handling of the water-valve is therefore not necessary and the loss of water is avoided. The overflow may be placed in any convenient position for ready and convenient observation by the engineer, and the proper start of the injector can be readily ascertained by him.

The operation of the injector is as follows: The water-valve T being open, the screw-spindle N is turned about one-fourth of a turn by means of handle S. This will lift valve M from its seat and admit steam to nozzle F. Any hot water accumulated in the injector-body itself and in pipe Y will be expelled through the overflow by this priming-jet F, and cool water from the tank will follow immediately. When water appears at the overflow, the spindle N is further turned, and when valve M strikes the collar P on top of valve L this latter will be opened and steam admitted to nozzle E. The combined effect of the two steam-jets will be to force the water through nozzles G, H, and I with sufficient velocity to enter the boiler. The quantity of water delivered in proportion to the steam-pressure will be regulated by valve T.

The present drawing shows a central priming-jet F and annular forcing-jet E. This can be reversed and the primer made annular and the forcing-jet central.

Other details of construction may be varied without departing from the spirit and principle of our invention.

We are aware that lifting-injectors have been made with a central or annular lifting jet or primer, and that such lifting-injectors could be and have been used as non-lifters; but when so used the primer has had no distinct function of its own to perform, as (the overflow being below the water-level) the injector did not require any priming, the water flowing through the overflow by its own gravity. We believe ourselves to be the first, however, to have used a primer with an elevated overflow in a non-lifting injector or to have used in conjunction with a non-lifting injector an overflow, so situated that when the water-valve is open water from the tank will not escape through it by gravity.

What is claimed as new, and desired to be secured by Letters Patent, is—

1. A non-lifting injector with an elevated overflow to retain the water in the supply-tank without the necessity of closing the water-valve, substantially as described.

2. A non-lifting injector with a priming-jet, when the overflow of the injector is so situated that the water will not escape through it by gravity, substantially as described.

3. A non-lifting injector with a priming-jet, in combination with an elevated overflow, as and for the purpose set forth.

4. An injector situated below the lowest water-level in the supply-tank, with an overflow situated above the highest water-level in the supply-tank, as and for the purpose set forth.

5. An injector situated below the lowest water-level in the supply-tank, with an overflow situated above the highest water-level in the supply-tank, the injector and overflow communicating through an external pipe leading from the injector to the elevated overflow, as and for the purpose set forth.

6. An injector with a detached overflow, situated at different levels and communicating with each other through an external pipe leading from the lower level of the injector to the higher level of the overflow, substantially as described.

In testimony whereof we affix our signatures in presence of two witnesses.

LEOPOLD KACZANDER.
ROBERT RUDDY.
